UNITED STATES PATENT OFFICE.

ERNEST N. RYDER, OF BREWSTER, NEW YORK.

HOLDER FOR X-RAY TUBES.

1,120,748.

Specification of Letters Patent. Patented Dec. 15, 1914.

Application filed December 12, 1913. Serial No. 807,726.

To all whom it may concern:

Be it known that I, ERNEST N. RYDER, a citizen of the United States, residing at Brewster, in the county of Putnam, State of New York, have invented certain new and useful Improvements in Holders for X-Ray Tubes; and I do hereby declare the following to be a full, clear, and exact description of the invention, such as will enable others skilled in the art to which it appertains to make and use the same.

The present invention is directed to improvements in holders for X-ray tubes, and has for its object to so construct a holder of this nature that the X-ray tube can be properly held for directing its rays upon the head of a patient.

A further object of the invention is to provide a holder of this character which is exceedingly simple in construction, and one which is so constructed that it may be swung out of the way when the tube is not in use.

A still further object of the invention is to provide an X-ray tube holder so constructed that the same can be adjusted in proper respect to the patient's head, and the tube moved in a circle so as to direct the rays to the proper place upon the head of the patient.

With these and other objects in view, this invention resides in the novel features of construction, formation, combination and arrangement of parts to be hereinafter more fully described, claimed and illustrated in the accompanying drawing, in which:

Figure 1 is a side elevation of the device. Fig. 2 is a detail perspective view of the tube support. Fig. 3 is a detail sectional view of the means for securing the tube carrying bar and the carrying arm together. Fig. 4 is a similar view showing the means for allowing the tube carrying frame to have movement about a vertical axis.

Referring to the drawing, the numeral 1 designates a bracket, which is adapted to be secured to the side of the wall. Supported by the bracket 1 is an arm 2, to which is adjustably connected an arm 3, said arms being disposed in horizontal position. The outer end of the arm 3 is provided with a

bearing 4 in which is rotatably mounted the trunnion 5 which is formed upon the upper end of the vertical bar 6. The trunnion 5 is adapted for rotation in the bearing 4 and is held therein by the cross pin 7.

The tube support 8 consists of a horizontal bar 9 having depending from its ends bars 10, one of which is provided with a bearing 11, while the other is provided with an open bearing 12. To attach the X-ray tube 13 to the support the extension 14 thereof is inserted in the bearing 11, after which the tube is swung so that the extension 15 thereof is engaged in the bearing 12.

The usual extension 16 of the tube is connected to the lower end of the cord 17, the upper end of which is adapted to be secured to any one of the vertically alined hooks 18 so that the rays from the tube can be directed at the desired angle upon the patient's head, said hooks being supported upon the arm 19 which has its lower end connected to the bar 9 and its upper end connected to the lower end of the bar 6 by a clamping bolt 20. The clamping bolt 20 can be manipulated so as to hold the arm 19 at different angular relations to the bar 6, and as the bar 6 is rotatably connected to the arm 3 the tube support 8 can describe a circle around the head of the patient so as to direct the rays of the tube to the desired spot. By pivotally connecting the bar 6 and arm 19 it is obvious that the tube support can be swung upwardly and out of the way, and held in this position in any suitable manner. When the tube support 8 is swung to its inoperative position it is obvious that the arms 2 and 3 can be swung against the wall, as the bracket 1 is pivotally mounted upon the clips 21.

What is claimed is:

In a device of the class described, the combination with a bracket, of arms supported by the bracket, one of said arms having a hole formed in its outer end, a bar having a vertical pin formed upon its upper end, an arm adjustably connected to the lower end and arranged to extend vertically through the hole of the bar on a horizontal pivot, means for maintaining the bar in its

adjusted positions, a support fixed to the lower end of said arm, an X-ray tube carried by the support, and a flexible connection between the tube and said arm for holding said tube in adjusted positions to direct the rays therefrom in different directions, as and for the purpose set forth.

In testimony whereof, I affix my signature, in the presence of two witnesses.

ERNEST N. RYDER.
